UNITED STATES PATENT OFFICE.

AUSTIN C. LARR, OF LITTLE ROCK, ARKANSAS.

BOAT FOR SHALLOW WATERS.

No. 921,849.

Specification of Letters Patent.

Patented May 18, 1909.

Application filed June 19, 1907. Serial No. 379,724.

To all whom it may concern:

Be it known that I, AUSTIN C. LARR, a citizen of the United States, residing at Little Rock, in the county of Pulaski and State 5 of Arkansas, have invented a new and useful Improvement in Boats for Shallow Waters, of which the following is a specification.

This invention is a boat adapted especially for use in shallow waters and in streams having sandbars and shoal places of other easily displaced material such as silt and the object 10 of the invention is to provide means whereby the boat can remove from its path the disintegrated portions of the bar and throw it 15 upon one side thus excavating through the bar a passage for the main body portion of the boat.

A further object of the invention is to arrange the propelling mechanism so that it 20 will aid in conveying out of the depth of the boat the dislodged material thus making it unnecessary to supply a double mechanism.

The invention consists of a boat having a reduced prow portion upon the sides of which 25 are secured a flume the prow having a sheer and the propellers being arranged at the rearward ends of the flumes thereby causing a rapid flow of water through them carrying with it the displaced material and throwing 30 the same upon either side of the boat.

In the drawings:—Figure 1 is a plan view of the forward portion of a boat portions being in section. Fig. 2 is a side view, a portion of the flume being broken away and 35 partly shown in section.

In these drawings A represents the boat having a prow portion A' reduced in width and provided at its forward end with a plow B adapted to excavate through a bar of sand 40 or other similar material.

In the rear of the prow and upon each side of the reduced portion of the prow I arrange flumes C open at each end. The forward end of each being provided with slats C' which 45 prevent obstructions from entering the flume and fouling the propeller. A sheer A² is formed upon the prow A' which sheer

forms the rearward and inner wall for the flumes, which therefore open at their rear ends at an oblique angle to the keel of the 50 vessel. Suitable propeller shafts D extend into these flumes also obliquely with respect to the keel and these shafts carry propeller blades D'. They are driven by engines E of any type and to aid in the forcing of water 55 through the flumes and the removal of the sand or other dislodged material I provide a pump E', and a suction pipe F which takes the water from the under side of the prow and discharges it through two discharge 60 pipes F' which extend forwardly and pass out through opposite sides of the prow and then bend downwardly and rearwardly discharging water in the direction of the mouth of the flumes and thus aiding in creating a 65 rapid current through the flumes which will carry away all sand and other materials thrown up by the plow B.

It will be obvious that any form of propellers may be employed and any suitable 70 style of engines and pumps that is desired, the jets of water thrown by the pipes F' may be dispensed with and the propellers only depended upon to cause rapid circulation of water through the flume. 75

Having thus fully described my invention, what I claim as new and desire to secure by Letters Patent, is:—

The combination with a vessel having its forward end portion reduced in width, flumes 80 formed upon said reduced portion and upon opposite sides of the boat, said flumes being open at each end and discharging rearwardly in an oblique direction with respect to the keel of the boat, propellers arranged at 85 the rearward ends of the flumes, and means for discharging jets of water in advance of the flumes and downwardly and rearwardly, as and for the purpose set forth.

AUSTIN C. LARR.
